UNITED STATES PATENT OFFICE.

CLEAVER M. LIPHART, OF RICHMOND, VIRGINIA.

DESIGN FOR A STOVE.

No. 38,172.

Specification for Design.

Patented Aug. 14, 1906.

Application filed May 28, 1906. Serial No. 319,213. Term of patent 7 years.

To all whom it may concern:

Be it known that I, CLEAVER M. LIPHART, a citizen of the United States, residing at Richmond, in the county of Henrico and State of Virginia, have invented a new, original, and ornamental Design for Stoves, of which the following is a specification, reference being had to the accompanying drawing, forming a part thereof.

The figure is a perspective view, in side elevation, of a stove, showing my new design.

I claim—

The ornamental design for a stove, as shown.
